UNITED STATES PATENT OFFICE.

REINHOLD M. WENDEL, OF AIGION, GREECE.

CENTRIFUGAL CONCENTRATOR.

Application filed December 19, 1927, Serial No. 241,236, and in Sweden October 7, 1926.

This invention relates to centrifugal machines for a mechanical concentrating of liquid mixtures or in fluids suspended solids. The invention is especially adapted for paper mills or factories and has for its main object to provide a thoroughly efficient machine to recover the paper fibres, which usually are wasted with the escaping water. Without any material change in its design the invention proved machine, however, can be utilized for any other class of manufacture where similar conditions occur.

Another object of the invention is the provision of a concentrator by which the concentrating process is combined with a lifting of the mixture from a lower receptacle to a higher receptacle solely by means of the centrifugal force which effects the concentration also.

Another object is a concentrator in which a recollection of the solid constituent can be continuously carried out whereby also solids of a rather light specific gravity and mixed with a rather large quantity of the fluid can be readily recollected.

A still further object of this invention is the provision of a concentrating machine in which the mixture is caused to pass more than one concentrating device for the purpose of treating mixtures containing constituents of rather different specific gravities.

Further objects and advantages will appear in the following description.

For a full understanding of the invention and the merits thereof and also to acquire a knowledge of the details of construction and the means for effecting the result reference is to be had to the following description and accompanying drawings, in which—

Figure 1 is a diagrammatic sectional elevation of an embodiment of the invention with three discharge passages for the constituents of the mixture;

Figure 2 is a similar view of another embodiment of the invention on a smaller scale but with the same arrangement of discharge passages;

Figure 3 is a similar view of a third embodiment of the concentrator with other kinds of discharge passages and with pocketlike projections;

Figures 4 and 5 are plan views of the concentrator in Fig. 3, the pockets being in rectangular arrangement and the means control-

ling the discharge adjusted to different positions;

Figures 6-8 are plan views of the last mentioned embodiment in the concentrator with pockets of variable numbers and forms;

Figure 9 is a sectional elevation of a fourth embodiment of the invention;

Figure 10 is a section of the last mentioned embodiment on a reduced scale and with the upper portions removed;

Figure 11 is a sectional elevation of a further embodiment of the invention, and

Figure 12 a sectional view similar to Fig. 10 of the last mentioned embodiment.

Corresponding and similar parts are referred to in the following description and indicated in all the views of the drawings by the same reference characters. The embodiments as well as their function are described in the following in the same order as they are shown in the drawings.

In Fig. 1 the concentrator is shown as comprising a substantially conical drum 1, the shaft 2 of which is vertical as are the shafts in all the other embodiments. The end of the shaft 2 is supported by a thrust bearing 3, and near the top it is guided by a neck bearing 4, above which the shaft is provided with a pulley 5 driven from some source of energy. The thrust bearing 3 is integral with or in other way supported by a receptacle or basin 6 wherein the mixture to be concentrated is collected, and from which the mixture is to be lifted up to a receptacle on a higher level. The mixture to be treated in the following is assumed to be the waste fluid from paper-making in which fibres and other solid constituents of the paper pulp are suspended.

The lower end 1' of the conical drum is submerged in the mixture in the low level receptacle 6 and is provided with an opening 7 for the entrance of the mixture into the drum.

The top end 1'' of the upwardly flared drum is open, and according to the embodiments in Figs. 1 and 2 provided with either one funnel-shaped discharge distributor 9 (Fig. 2) or more than one such distributor 8 and 9 (Fig. 1) telescopic therein. Said funnels preferably are adjustable axially for instance by means of keys 10', 10'', 11', 11'' respectively on the shaft 2, whereby the annular discharge passage 12 between drum 1 and funnel 8, and the discharge passage 13 between the two funnels 8 and 9 (Fig. 1) or the single

passage 120 between drum 1 and funnel 8 (Fig. 2) can be varied for the discharge of variable quantities of the constituents of the mixture. The discharge passages 12, 120 respectively 13, 14 communicate with stationary annular spaces or compartments 17 respectively 18, 19 separated from each other, and provided each with an outlet 20 respectively 21, 22. The outlet 20 communicates 5 with the pulp tank, representing the high level receptacle but not shown in the drawing, the outlet 21 communicates with the low level receptacle 6, and the outlet 22 communicates for instance with the main drain channel of the mill. The compartments 17, 18, 19 are supported by a frame work 23 on a suitable foundation (in Fig. 1 the bottom of the low level receptacle 6). Somewhat remote 10 from the down end the drum 1 is provided outwardly with a collar 24 for the purpose of removing such fluid as may have adhered to the drum.

Stiffening arms 27 for the drum may be of a shovel-like screw form so as not to impede the rising movement of the mixture 15 within the drum.

According to the embodiments shown in Figs. 3-8 the drum 1 along the circumference is provided with radially projecting pockets 30^a-30^d of any arbitrary number, but disposed symmetrically around the revolving shaft 2 in order to maintain the stability of the machine when rotating. The pockets suitably are of such a form, that the circular cross section of the drum in Figs. 1 and 2 is 20 substituted by a polygon with straight or curved sides. The simplest embodiment is shown in Fig. 6 with two diametrically opposed pockets 30^a, 30^b which, viewed from above, form two angles the sides of which 25 make tangents to the circular section of the drum. In Figs. 7 and 8 the pockets are three in number being the corners 30^a 30^b and 30^c of a triangular compartment with plane sides 30 according to Fig. 7 and concave sides according to Fig. 8, the last mentioned shape for the purpose of obtaining rather acute angles, which advantageously effects the result of the device. Figs. 4 and 5 show a design with 40 four pockets 30^a, 30^b, 30^c and 30^d forming a rectangle. The vertical sides 31^a-31^d of the pockets may in all the embodiments touch the greatest circumference of the drum, in order to facilitate the centrifugal delivery of the 45 concentrates into the pockets.

The drum and pockets are closed at the top by a cover 32 with a central aperture 33 for the drum shaft 2. In the cover 32 swinging nozzles 34^a, 34^b, 34^c and 34^d are provided, a 50 nozzle on the top of each pocket near the point of its angle. A number of discharge openings for instance two, 35^a, 35^b, provided with radially adjustable slides 36^a, 36^b, are disposed nearer the centre line and communicate 55 with pipes 37^a, 37^b with adjustable outlets

not shown in the drawing, which pipes extend to the uppermost compartment 19. The nozzles 34^a-34^d end in the lowermost space 17, which extends as near the centre line of the drum as possible. The number of the 70 discharge openings 35^a, 35^b must suit the capacity of the concentrator and the kind of fluid to be treated therein.

The hitherto described substantially circular drum 1 is in the embodiments in Figs. 75 9-12 substituted by a drum the cross section of which shows a polygon with sharp or rounded corners which constitute the portions of the drum most remote from the centre line. In Figs. 10 and 12 four such corners 80 30^a, 30^b, 30^c, 30^d are shown, but the number is optional and must suit the working and constructional circumstances. The corners lie in the direction of the producer of the drum either along the whole length thereof or along 85 its upper portion only, the last mentioned design being a transitional form from the pockets in Figs. 3-8. While the corners as well as the pockets are the portions of the drum most remote from its centre line, they 90 will be accumulating spaces for the concentrates. As the concentration depends to a certain degree on the time during which the mixture is exposed to the influence of the most effective centrifugal force, and as this 95 time of influence on the other hand depends on the axial length of the corners, it is easily understood, that the axial length of the corners may be chosen according to the kind of mixtures to be treated.

Like the embodiment in Fig. 3 the concentrator drum in Fig. 9 is closed at the top by a cover 32 provided with openings 35^c, 35^d with radial slides for the discharge of the liquid which has been freed from the suspended solids, to the lower stationary collecting compartment 19 at the upper border of the drum. In the horizontal plane swingable discharge nozzles 34^c, 34^d, 34^e, 34^f communicate with the other stationary collecting compartment 17 positioned above the compartment 19 (only two collecting compartments are shown according to the simplest embodiment of the invention) for the collecting of the concentrates from the upper portions of 105 each corner 30^a...30^d respectively. The inlet 7 of the concentrator drum in this embodiment is so designed, that the mixture in the low level receptacle 6 is pushed into the drum by the outer static pressure only without necessarily submerging the drum into the mixture itself.

The embodiment shown in Figs. 11 and 12 is a further development of the apparatus for continued concentrating of the contents. The concentrator drum 1 here is provided with an outer shell 40 of essentially the same form as the single shell in Fig. 9, which in Fig. 11 constitutes the inner shell and is designated by 39. Between the outer and in- 115 120 125 130

ner shell there is a space 100 forming an annular outer drum. The lower portion of the space 100 communicates with the upper portion of the inner drum relatively near the 5 centre line as shown in Fig. 11 by means of obliquely and substantially radially disposed tubes 41 within the inner drum. Said tubes 41 conduct the lighter constituents which during the rotation of the drum are deprived 10 of the heavier constituents out to the outer drum 40. The cover 32 on the inner drum is extended over the outer drum and in the corners provided with discharge nozzles swingable in the horizontal plane viz in the 15 outermost corners pipe nozzles 42^a, 42^b, 42^c, 42^d for the concentrates and inside thereof nozzles 43^a, 43^b, 43^c, 43^d for the separated liquid. The outermost nozzles 42 as well as the discharge nozzles 34 of the inner drum 20 open into the uppermost stationary collecting compartment 17, and the inner nozzles 43 (as the openings 35 of the single drum) discharge into the lower stationary collecting compartment 19. If desired there is no objection 25 for a further dividing of the discharged constituents for instance through the provision of separate collecting compartments for the nozzles 42 and 43.

The operation of the different embodiments 30 of the machine is to be clearly understood by the following.

The principle of the operation will appear most easily from Fig. 2. The noninterrupted 35 upwardly flaring form of the concentrator drum causes the liquid which enters the bottom opening 7 to rise along the shell when it is thrown outwardly by the centrifugal force against the shell of the drum 1 and thereby brought to take part in the rotation of the latter. At the same time the mixture in a known manner becomes separated, so that the heavier constituents (the fibres of the waste pulp) are accumulated on the shell of the drum. When thus the mixture is lifted 40 to the upper border of the drum, the concentrates pass out through the annular passage 120 into the stationary compartment 17 and discharge through the outlet 20. The specific lighter constituents which are held more remote from the shell of the drum flow over the 45 lower edge 90 of the partition funnel 9, and discharge through the higher opening 14 into the stationary compartment 19 from which they escape through the outlet 22.

If the partition funnel 9 is moved axially upwards or downwards the annular passage 120 will be wider respectively narrower, so that a thicker layer respectively a thinner one is admitted through said opening. Various 50 degrees of concentration of the mixture discharge through the outlet 20 is effected. Because of the essentially conical shape of the drum in combination with a suitable speed of revolution the improved concentrator 55 procures the concentrating of the mixture as

well as the lifting of the same to a desired level.

It is diagrammatically shown in Fig. 1 how the rising mixture is divided into layers, so that the layer 25 which is most rich in 70 solid constituents will more closely approach the shell of the drum, and the more the layers of the mixture are remote from the shell the poorer they are in fibres or other solid constituents, so that the innermost layer 16 consists substantially in pure water without any noteworthy suspended solids. Naturally the layers are not defined so distinctly as indicated in the drawing but smoothly floating into each other. The layer 25 most rich in 75 solids discharges at the top through the passage 12 into the compartment 17 and is carried by the pipe 20 to the pulp tank not shown in the drawing. An intermediate layer 26 containing less of solids is discharged 80 through the annular passage 13 between the two funnels 6 and 9 into the compartment 18 and conducted back to the low level receptacle 6 by the pipe 21. At last the innermost (water-) layer 16 discharges through the innermost annular opening 14 to the compartment 19 whence it goes to the main drain channel of the mill through the pipe 22. The percentage of fibres or other solids in 85 the layers 25, 26 as already mentioned is controlled by the axial adjustment of the funnels 8, 9 by means of the keys 10', 10'', 11', 11''. An adjustment upwardly reduces the concentration of the layers 25, 26 and will at the same time increase the quantities 90 discharging into the compartments 17, 18.

As the layer 25 only has a degree of concentration suitable for the mass in the pulp tank, only this layer must be supplied to said tank. However, it would be an undesirable 100 waste of fibres, if the next layer 26, which still is rather rich in fibres, would be allowed to escape through the main drain channel, and in order to avoid such a loss of material said layer is conducted back to the low level 105 receptacle 6 to pass the concentrator once again together with the fresh quantity of waste mixture supplied directly from the paper-making wire.

When the concentrator is used to recharge 110 the waste fibres into the pulp tank the concentrator in many cases must be made comparably high, because the pulp tank always is disposed on a rather high level above the low level receptacle 6. The revolving speed 115 of the drum 1 as well as its conic angle are to be chosen in view thereof.

In the embodiments shown in Figs. 3-8 the heaviest constituents by the force of rotation 120 will be thrown out into the pockets 30^a-30^d the shape of which is such that without any risk, even very thick constituents will clog the outlet openings. From the pockets the 125 concentrates are forced out through the swinging and comparably wide nozzles 130

34^a—34^d into the compartment 17 from where they escape through the outlet 20. The quantity of the discharged concentrates which controls the possible degree of concentration depends upon the position of the nozzles during the rotation of the drum. The more the nozzles are swung inwards towards the centre line of the drum the greater becomes the counteracting pressure caused therein by the centrifugal force and the thicker the concentration is. Fig. 4 shows the position of the nozzles at a low degree of concentration and Fig. 5 said position at a high degree thereof. Thus the variation of the percentage of concentration here is not obtained by any variation of the outlet area, and that brings with the great advantage, that the outlets maintain the same width under all the circumstances whereby all risk of clogging is avoided also at the thickest degree of concentrations. The separated liquid escapes through the discharge openings 35^a, 35^b in the cover and through the pipes 37^a, 37^b into the upper compartment 19 and thence through its outlet 22. The position at the slides 36^a, 36^b as well as the adjustment of the sectional areas of the pipes 37^a, 37^b depend on the position of the substantially vertical surface of the centre cavity of the liquid within the drum 1 as well as of the desired degree of concentration.

In the embodiment according to Figs. 9 and 10 with an angular concentrator drum the corners of said drum act as extended pockets with the advantage of a highly increased degree of concentration. The double or multiple device shown in Figs. 11 and 12 is especially adapted for such mixtures which contain solid constituents of very different specific gravities. In such a case the lighter constituents would require such a high speed of revolution, that the heavier constituents would stick to the shell of a single drum. The mixture to be treated in this double or multiple drum enters through the bottom entrance 7 of the inner drum and is driven upwards by the centrifugal force during the rotation whereat the angular form of the drum, beginning already near the entrance of the liquid, causes a strong concentration as a result of the heaviest concentrates accumulating in the longitudinal corners of the drum. This concentrate separated in the inner drum escapes at the top thereof through the corner discharge nozzles 34 into the compartment 17 and flows out from here through the outlet 20. The mixture yet containing the lighter constituent at the top of the inner drum enters the tubes 41 the ends of which are cut oblique, and the tubes conduct said mixture to the lower portions of the outer drum 100, in which the mixture again is submitted to the centrifugal force and moved upwardly whereby on account of the larger radius of the outer drum a so much stronger force is set

up than that in the inner drum, that also the lighter constituents are separated without necessity of such a high speed of revolution that the heavier concentrates would be caused to adhere to the shell of the inner drum. The concentrates from the outer drum escape through the outmost discharge nozzles 42 into the collecting compartment 17, while the separated liquid flows through the inner discharge nozzles 43 of the outer drum into the collecting compartment 19.

Thus the multiple device effects a continued concentration of certain portions of the mixtures for somewhat the same purpose as that of the reconducting device in Fig. 1. The multiple device also gives the same result at a low revolving speed of the drum when treating a light material as does a single drum with a higher speed of revolution. The operation of the single drum without the outer drum as shown in Figs. 9 and 10 is easy to understand from the above description without any further explanation. It is evident, that the more the corners of the drum are remote from the other portions of the circumference of the drum, the higher degree of concentration will be obtained without increasing the revolving speed. The multiple device naturally is not limited to a polygon concentrator drum only but can be used with the same result also in the embodiments shown in Figs. 1-8 with a circular drum.

In all the embodiments of the invention shown and described an intermediate product can be carried back to the low level receptacle 6 as shown in Fig. 1 to be submitted to further concentration.

The embodiments shown in the drawings are to be considered as examples only for the understanding of the invention as various changes in the construction and arrangement of the several parts can be made without departing from the spirit of my invention as disclosed in the appended claims.

Having thus described my invention what I claim is:

1. A centrifugal concentrator for solids suspended in liquids comprising a vertically disposed rotary drum of an essentially cone like shape flaring upwardly along its entire length, a low level receptacle for the liquid mixture to be treated, and a high level receptacle for collecting of the concentrate, the down end inlet of said drum submerging into the low level receptacle, the drum surrounded by an outer drum of substantially the same form as said inner drum, both the drums provided with outlets for constituents of various specific gravities, the outlets for the heaviest constituents communicating with the high level receptacle, and means to communicate the outer drum with the inner drum.

2. A centrifugal concentrator for solids suspended in liquids comprising a vertically disposed rotary drum of an essentially cone

like shape flaring upwardly along its entire length, a low level receptacle for the liquid mixture to be treated, and a high level receptacle for collecting of the concentrate, the 5 down end inlet of said drum submerging into the low level receptacle, the drum surrounded by an outer drum of substantially the same form as said inner drum, both the drums provided with outlets for constituents of various 10 specific gravities, the outlets for the heaviest constituents communicating with the high level receptacle, and tubes communicating the lower portion of the outer drum with the upper inner portions of the inner drum relatively near the centre line thereof.

3. A centrifugal concentrator for solids suspended in liquids comprising a vertically disposed rotary drum of substantially cone shape, flaring upwardly along its entire 10 length, a low level receptacle for the liquid mixture to be treated, and a high level receptacle for collecting the concentrate, the lower inlet end of said drum being submerged in the low level receptacle, the drum being provided with lateral pockets forming narrow 15 corners, said pockets being provided with out-

lets extending inwardly from said corners, the drum being provided with outlets for the heaviest constituents communicating with the high level receptacle as well as outlets for 30 the other constituents of the mixture.

4. A centrifugal concentrator for solids suspended in liquids comprising a vertically disposed rotary drum of substantially cone like shape flaring upwardly along its entire 35 length, a low level receptacle for the liquid mixture to be treated, and a high level receptacle for collecting the concentrate, the lower inlet end of said drum being submerged in the low level receptacle, the drum being provided with laterally projecting pockets forming corners in their outmost portion and provided with outlets for the heaviest constituents communicating with the high level receptacle, and means to adjust the outflow of 40 said outlets, said means including nozzles adapted to be swung in a horizontal plane to vary the position of their outlet ends with respect to the center of said drum.

In testimony whereof I have affixed my signature. 50

REINHOLD M. WENDEL.
